JAMES P. BURKE, OF WAYNE, NEW JERSEY, ASSIGNOR TO KEPT-KAPT, INC., OF KNOXVILLE, TENNESSEE, A CORPORATION OF DELAWARE

CONTAINER AND CLOSURE THEREFOR

Application filed October 23, 1931. Serial No. 570,741.

This invention relates to containers and closures therefor, having particular reference to collapsible tubes. One object of the invention is to provide an improved mounting of a rotatable closure on a tubular element such that the closure is reliably permanently mounted on said element and has continuous sealing coaction to prevent leakage between the element and closure.

Another object of the invention is the provision of a rotary closure on the neck portion of a collapsible tube, and having improved stop engagement therewith. Another object of the invention is to furnish improved means for spinning sleeved relatively rotatable tubular devices into engagement with each other, and particularly to interiorly press an outward locking projection portion, such as an annular ridge in the inner device, and/or spinning the inner device into snug seating coaction with the outer device for affording a liquid tight seating for a valve closure or the like.

Another object of the invention is to provide an improved method of making or interengaging a plurality of relatively rotatable elements such as a tubular element and a valve cap thereon, whereby the element is pressed or spun into snug seating contact with the cap and/or an outward projecting annular portion formed in the element for snugly engaging throughout in a corresponding recess or undercut in the cap, whereby to afford a liquid tight locking engagement for the cap.

A further object of the invention is to produce a simplified closure in an inexpensive manner, by easily operable means, so as to obtain a durable, reliable and efficient device.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein

like parts are designated by the same reference characters throughout the several views.

In the drawing:

Figure 1 is a view in elevation showing a device embodying the invention. 55

Fig. 2 is a fragmentary view in elevation of the device taken at an angle to Fig. 1.

Fig. 3 is a sectional view taken on line 3—3 of Fig. 2.

Fig. 4 is an enlarged sectional view of the 60 device.

Fig. 5 is a sectional view showing a step in the method of making the device.

Fig. 6 is a view with parts in section showing a subsequent step in the method of making the device, and the apparatus employed, 65 with parts removed.

Fig. 7 is a sectional view taken on line 7—7 of Fig. 6.

Fig. 8 is a still further enlarged sectional 70 view showing the device in course of manufacture.

The advantages of the invention as here outlined are best realized when all of its features and instrumentalities are combined 75 in one and the same structure, but, useful devices may be produced embodying less than the whole.

It will be obvious to those skilled in the art to which this invention appertains, that 80 the same may be incorporated in several different constructions. The accompanying drawing, therefore, is submitted as showing the preferred exemplification of the invention. 85

It has heretofore been known to provide rotatable valve closures for collapsible tubes, with the closures held on by a detent or sprung over a suitable projection on the tube. In such devices, auxiliary means was 90 found necessary to prevent occurrence of leakage between the closure and the part of the tube sleeved therein, as, for example, special resilient inserts at the valve opening, or cams for drawing the closure snugly 95 against the tube part in the closed position. By my invention these features are eliminated, whereby the device may be much more cheaply made, in quantity production, and without permitting leakage, and so as to be 100

substantially liquidtight for the materials handled in the collapsible tubes.

Generally described, I provide a collapsible tube having a substantially cylindrical portion of reduced diameter provided with a closed hemispherical end. Upon this is placed a cap of similar contour and having an internal annular coaxial groove. The tube part is interiorly spun to force a ridge 5 into said groove, the expansion causing the tube part to uniformly snugly seat in the cap in a liquid tight manner. Simultaneously the hemispherical end may also be spun or expanded to snugly contact the inside face of the cap to afford a tight valve seat at the outlet openings that may be provided at a suitable step in the manufacture of the device. Thus in one operation the cap is permanently rotatably secured to the collapsible tube and caused to be individually fitted thereto in a tight manner, eliminating the effects of any possible variations in size or form of the cap or tube or both, in course of their separate manufacture, and 15 due to the different natures of the materials employed.

Referring in detail to the drawing, 10 denotes a device embodying the invention. The same may include a tubular device such as a collapsible container 11 having a neck portion 12 of reduced diameter. The container and its neck portion may be of any conventional construction and may consist of a soft ductile or pliable metal. Preferably the neck portion is of substantially cylindrical form, and may terminate in a portion 13 of reducing size, of taper form, or merely hemispherical as shown. At the base of the neck portion there may be a stop member 14 which may be integral therewith.

Rotatably mounted on the tubular or neck portion 12 there may be a coacting tubular device such as a cap 15. This may be relatively rigid and made of any material, such as metal, bakelite, or other relatively strong or non ductile material. Interiorly the cap fits the neck portion snugly. To retain the cap on the neck portion, the cap may have an internal preformed undercut or annular groove 16 into which a corresponding annular flange or ridge 17 of the neck portion may be spun or depressed for a snug and somewhat resilient engagement. The location of this line of engagement may be intermediate of the ends of the closure 15, and preferably in suitable proximity to the end 13 which may act as a re-enforcement for the ridge 17. In this manner, moreover, the closure may be made with a minimum length. The groove and ridge engagement also serves to retain the curved end 18 of the cap in snug contact with the corresponding part 13. It will be noted that the ridge and 65 groove have a plurality of curves forming

substantially a U in shape to assure a uniform and ample area of contact.

The end portion of the neck may have an opening 19 offset from the center, and the closure may have a corresponding opening 20 adapted to register therewith. Between the portions 13 and 18 is the snug valve seating surface 20a for the openings 19 and 20. At 21, the closure may be outwardly flared from the opening 20.

The lower part of the closure may have an enlarged finger grip portion 22. Within the same there may be an arcuate recess 23 for receiving the stop 14 the ends of the recess defining stop faces of an angularly elongated shoulder 24, for abutment with the stop 14, and whereby the open and closed positions of the cap are determined.

The device above described is particularly characterized by the fact that the interlocking engagement at 16, 17 forms a seal which supplements the seal at the surface 20a. The latter is likewise rendered snug preferably by outward pressing or spinning of the hemispherical portion 13 simultaneously with the formation of the annular projection 17. Thus, not only is any tendency overcome of collapsing the part 13 downward due to the outward pressure at 17, but the part 13 is actually positively outwardly pressed for an individual fit with the cap.

In manufacturing the device, the cap may be initially provided with the opening 20 bounded by an angular edge 25 terminating in the flare 21. A tubular neck portion 12, having a uniform side wall 26 is placed therein. Then the neck portion is interiorly spun to expand the same to form the ridge 17 and simultaneously to press the hemispherical part 13 for a good valve seat with the corresponding cap part 18. The opening 19 may have been previously formed or may now be drilled, and the opening 20 reamed to eliminate any burr and thereby 105 form the straight edges 27 for the opening 20.

Any suitable means such as 28 may be used to effect the spinning of the neck portion. Thus a tool may be utilized having a 115 head 29 provided with a centering or tapering end 30 that may be hemispherical and of suitable size to snugly fit the end of the neck portion. This head may be hollow and may have a laterally projectable element or 120 pin 31 slidably fitted in a hole in the wall thereof. Suitable means may be provided for actuating the head and pin. Thus a spindle 32 may extend into the head and may have means such as a tapering end or cone 33 for actuating the pin by laterally bearing on a head 34 thereof as a result of relatively longitudinal sliding movement of the head 29 and the stem 32 or a part 125 thereof. The provision of the head 34 pre- 130

vents the element 31 from leaving the head 29. To limit the relative movement of the parts 29, 32, the former may have a slot 35 and the latter a pin 36, movable therealong.

5 In this manner rotation may be imparted to the head 29 by the spindle.

Any well known means such as a gear 37 may be utilized for rotating the head 29. Longitudinal pressure on the head may be caused by an end thrust bearing 38 suitably actuated for the purpose. It will be noted that rotary and axial force may be simultaneously applied. Moreover, due to the application of axial pressure on the stem 32, the pin 31 is outwardly projected under a desired force and a pressure simultaneously exerted on the hemispherical end of the neck portion. As the ridge 17 is being formed the pin 31 moves outward from the head 29, and the stem 32 moves downward while rotating. Hence the neck portion is at the same time expanded laterally and longitudinally for a uniform continuous fit with the cap. Since the head 29 substantially fills the neck portion, any collapse of the latter due to pressure of the pin 31 at a point, is prevented, nor can the end 18 recede from the end 19 of the cap. After the spinning operation is completed 30 the head 29 may be withdrawn, the stem 32 moving upward relatively thereto, and the pin 31 backing up into its head.

In fact, I have found in actual practice that a portion of the neck 12, such as 39 shown in Fig. 8, may in course of the spinning operation be forced slightly into the opening 20 in the cap. This will happen to an imperforate part of the neck that will be adjacent to said opening, and the degree of such projection may be extremely slight, but sufficient to cause a very tight seal. The position of the part 39 is such that every time the cap is closed, the part 39 comes into registry with the opening 20 of the cap. 45 The base 40 may thereafter be suitably fastened to the device 10.

It will be appreciated that various changes and modifications may be made in the device as shown in the drawing, and that the same is submitted in an illustrative and not in a limiting sense, the scope of the invention being defined in the following claims.

I claim:

1. A closure device including a plurality of hollow members, one of the members being journaled upon the other, the members having openings adapted to register with each other, one of the members having an imperforate wall portion bulged into the opening in the other member when openings are out of registry, and the bulged portion being adapted to be sprung out of said opening on causing a relative rotation of the members.

2. A collapsible tube having a neck member, a cap member journaled on the neck

member, said members having openings adapted to be brought into registry with each other upon relative rotation between said members, the neck member having an integral outwardly bulging yielding wall 70 portion constituting a closure adapted to spring into the opening of the cap member upon relative rotation of said members to bring said openings into spaced relation to each other and to spring out of said opening upon different rotation between said members.

3. A collapsible tube having a neck member of soft metal, a cap member of a relatively rigid material, said neck member having an end wall, said cap member being journaled upon said neck member including the end wall thereof, and an opening at said end wall, said cap member having an opening adapted to be brought into registry with the opening of the neck member upon rotation of the former, said neck member having a portion having a slight outward closure bulge at said end wall, located so as to be adapted to releasably spring into the opening of the neck member when said openings are moved into offset relation to each other, said bulge being fitted to the opening of the cap member.

4. A collapsible tube having a neck of yielding material, said neck having a curved end wall, a cap of relatively rigid material journaled upon said end wall, the latter and said cap having openings adapted to be brought into registry upon relative rotation 100 between end wall and cap, said end wall having a fitted bulge portion adapted to yieldingly spring into the opening of the cap upon relative rotation of the end wall and cap with said openings in spaced relation to each other.

5. A collapsible tube having a neck provided with an arched end wall of revolution, a cap journaled upon said end wall for rotation between open and closed positions, said end wall and cap having eccentric outlet openings adapted to be brought into registry upon rotating the cap to open position, the end wall being in close engagement with 110 said cap at said end wall, means rotatably interconnecting said cap and neck to maintain the latter closely seated upon the cap, and the neck having an integral outwardly bulged closure portion which is curved so as to releasably spring into and out of the cap opening upon rotating the latter into opening and closing positions.

6. A collapsible tube neck of soft metal 125 for a rotary closure cap having an eccentric outlet opening, said neck having an opening and an outwardly formed integral bulge portion spaced from each other and from the axis of the neck and similarly located with respect to a plane perpendicular to the

axis of the neck so that said opening and
said bulge portion are alternately in regis-
try with the opening of the closure cap upon
rotation of the latter for opening and tightly
5 closing the cap opening.

In testimony whereof I affix my signature.

JAMES P. BURKE.
